(57) CLAIM

The ornamental design for a hat, as shown and described.

DESCRIPTION

FIG. 1 is a top, front, right perspective view of a hat showing my new design;

FIG. 2 is a front, perspective view thereof;

FIG. 3 is a rear, perspective view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate stitching and form a part of the claimed design.
